UNITED STATES PATENT OFFICE.

ROSS J. ELLSWORTH, OF CHICAGO, ILLINOIS.

DOOR FOR IN-A-CLOSET BEDS.

Application filed September 30, 1922. Serial No. 591,629.

To all whom it may concern:

Be it known that I, Ross J. ELLSWORTH, a citizen of the United States, and a resident of the city of Chicago, county of Cook, and State of Illinois, have invented certain new and useful Improvements in Doors for In-a-Closet Beds, of which the following is a specification.

My invention relates to new and useful improvements in doors for in-a-closet beds, and the like, and has for its object to provide a group of doors of this kind between a room and closet which are easy to operate and permit the attached furniture to be readily swung into or out of the room, and which are neat, convenient, and economical.

A further object is to provide convenient access to the closet, without moving the furniture and the attached door.

Other objects will appear hereinafter.

The invention consists in the combinations and arrangements of parts hereinafter described and claimed.

The invention will be best understood by reference to the accompanying drawings forming a part of this specification and in which,

Fig. 1, is a front elevational view,

Fig. 2, is a horizontal sectional view on line 2—2 of Fig. 1, and,

Fig. 3, is a sectional view similar to Fig. 2, but the doors being turned and the attached beds placed into the room.

In the drawings I have shown side walls 8 of a room or chamber 9 to which a closet 10 is attached and with which said closet communicates by means of a suitable opening. Doors for closing said opening are provided in similar sets or pairs of two each, and to one or more of said sets of doors is attached to an article or piece of furniture 11, as a bed, couch or similar article, by means of supporting plates 12 or the like.

In the drawings I have shown two sets or pairs of doors, this construction being particularly adapted for twin beds. Each set comprises two doors, 13 and 14, one of which is attached to the article of furniture 11 and the other of which is connected to said attached door by means of hinges 15, and one or more of said free doors is divided along an intermediate line and provided with hinges 15', to furnish a small door 14' and provide convenient access to said closet, as best seen in Fig. 3. A pair of pivot-pins 16 is passed through said supporting plates 12

of each set of doors and into the top sash frame 17 and the bottom sash frame 18, providing means for swinging each set of doors.

Each set of doors is also provided with a Pullman knob 19 or similar suitable device for conveniently operating the same.

By viewing Fig. 2, it will be observed that the free door 14 of the left hand set of doors is folded onto the attached door 13, and that the free door 14 of the right hand set is used to close the intermediate space between the two attached doors, while the articles or pieces of furniture 11 are concealed in the closet. To swing the articles 11 outward, the center door 14 is first folded against its attached door 13 and the right hand set of doors and article are swung or rotated 180° on the pivot pins 16, in the direction of the arrow "a"; then the left hand set of doors is rotated 180° in the direction of the arrow "b"; whereafter the free door 14 of the left hand set is swung out to close the intermediate opening; the members now being in the positions shown in Fig. 3, with the furniture or articles 11 in the chamber 9 and the opening between the chamber and closet being closed. The narrow door 14', at the same time, provides convenient access to the closet. Suitable retaining means, as snap fasteners 20 and 21, are provided to hold the attached doors together, in folded position.

While I have illustrated and described the preferred form of construction for carrying my invention into effect, this is capable of variation and modification without departing from the spirit of the invention. I, therefore, do not wish to be limited to the precise details of construction set forth, but desire to avail myself of such variations and modifications as come within the scope of the appended claims.

Having described my invention, what I claim as new and desire to secure by Letters Patent is:

1. A plurality of sets of similar doors mounted in the opening between a chamber and an annexed closet, an article mounted on each set of doors, hinge means to fold each set together to the width of a single door, pivot means to rotate each set on an intermediate axis within said opening and swing the article through an intermediate part of said opening, and a narrow door provided in one of said doors.

2. A plurality of sets of doors for closing

- an opening between a chamber and a closet, each set containing a plurality of doors of similar width and means for folding them together, a piece of furniture mounted on each set, and means to rotate each set on an intermediate axis and swing said furniture through said opening, a door of one set being unfolded and placed centrally of the opening in closing said opening.
- 10 3. A plurality of pairs of doors reversibly mounted in the opening between a chamber and an annexed closet, each pair of doors carrying an article and means for supporting said article on one of said doors, hinged means on each pair of doors for unfolding said doors to close said opening, and pivotal means located in said opening and engaging said supporting means for mounting each pair of doors to rotate said pairs in reverse directions thereon and swing their articles centrally through said opening.
- 15 4. A plurality of pairs of doors mounted in the opening between a chamber and an annexed closet, an article of furniture mounted on each pair of doors, hinges connecting the doors of each pair, and pivot means to rotate each pair, the doors of one pair only being unfolded to close said opening.
- 20 5. A double pair of doors mounted in the door opening between a chamber and its closet, a twin bed attached to a door of each pair, hinges connecting the free door to said attached door of each pair, and pivot means on the attached door of each pair for rotating said door and bed, said doors being folded to move said beds into or out of the closet and one of said doors being unfolded to close said opening.
- 25 6. The combination with a chamber and a closet having an opening there-between, a plurality of pairs of doors mounted in

said opening, means for folding or unfolding each set of doors, and means for rotating each set of doors to place the side of a door in each set in either said closet or said chamber, one of said doors being unfolded to close said opening.

7. The combination with a chamber and a closet having an opening there-between, a plurality of pairs of doors pivotally mounted in said opening, means for folding and unfolding each pair of doors, an article mounted on each pair of doors, the doors of one pair being unfolded to complete closing the opening when the articles are in the closet and the doors of another pair being unfolded to complete closing the opening when the articles are in the chamber.

8. A plurality of sets of doors mounted in the opening between a chamber and an annexed closet, a bed mounted on each set of doors, hinge means to fold each set, fastening means for holding the doors in each set together, and pivot means to rotate each set with the bed into said chamber or into said closet.

9. The combination with a chamber and a closet having an opening there-between, a plurality of sets of doors mounted in said opening, and means for folding and swinging said doors to close said opening with the side of a door in each set either in said chamber or in said closet, and clamping means for holding the doors in each set together.

In testimony whereof I have signed my name to this specification in the presence of two subscribing witnesses.

ROSS J. ELLSWORTH.
